(57) **CLAIM**

The ornamental design for a display screen or portion thereof with graphical user interface, as shown and described.

DESCRIPTION

FIG. 1 illustrates a front view of a first image in a sequence showing a display screen or portion thereof with graphical user interface.

FIG. 2 illustrates a second image thereof; and,
FIG. 3 is a detail of FIG. 2, shown enlarged for clarity of viewing.

The appearance of the images sequentially transitions between the images shown in FIGS. 1 and 2.

The process or period in which one image transitions to another image forms no part of the claimed design.

The peripheral broken lines depict a display screen and form no part of the claimed design. All other broken lines show portions of the graphical user interface and form no part of the claimed design.

1 Claim, 1 Drawing Sheet
